UNITED STATES PATENT OFFICE.

HANS RASMUSSEN, OF ROYAL, IOWA.

FUEL-FILTER FOR CARBURETERS.

1,221,376.

Specification of Letters Patent. Patented Apr. 3, 1917.

Application filed August 3, 1915. Serial No. 43,483.

To all whom it may concern:

Be it known that I, HANS RASMUSSEN, a citizen of the United States, and resident of Royal, in the county of Clay and State of Iowa, have invented a certain new and useful Fuel-Filter for Carbureters, of which the following is a specification.

My invention relates to filters for fuel for internal combustion engines.

10 The object of my invention is to provide a fuel filter for carbureters of simple, durable and inexpensive construction, and adapted to be connected with the fuel feed tube, and so constructed and arranged as 15 to properly filter the fuel just before such fuel is fed to the carbureter.

A further object is to provide such a filter so constructed and arranged that it may be readily and easily taken apart and 20 the filter member proper taken out and replaced.

Still a further object is to provide such a device so constructed and arranged as to be mounted on any engine, and particularly 25 shaped so as to be mounted on an automobile engine under the hood thereof.

Still a further object is to provide such a fuel filter device having a clean out passage conveniently located.

30 My invention consists in the construction arrangement and combination of the various parts of the device whereby the objects contemplated are attained as herein-after more fully set forth pointed out in my 35 claims, and illustrated in the accompanying drawings, in which:

Figure 1 shows a top or plan view of a fuel filter device embodying my invention.

Fig. 2 shows a side elevation of the same, 40 and

Fig. 3 shows a vertical sectional view taken on the line 3—3 of Fig. 2.

In the accompanying drawings, I have shown a preferred form of my invention. 45 My device comprises a casing made of two parts, which I have indicated in the accompanying drawings by the reference numerals 10 and 11. The casing is comparatively thin rather than spherical or thick 50 in order that it may be fitted into a small space under the hood of an automobile.

The part 10 of the casing is provided at its open end with an annular shoulder 12, and beyond the annular shoulder is an ex- 55 ternally screw threaded portion 13. The

part 11 is provided on its interior with an annular shoulder 14 and beyond the shoulder 14 is an internally screw threaded portion 15. The parts 10 and 11 may be screwed together and may be quickly and easily assembled or taken apart.

Between the portion 13 and the shoulder 14 is placed a comparatively rigid partition or disk 16, having near its upper end an opening 17 to permit the discharge of fuel. 65 Between the partition 16 and the portion 13 is secured the edge of a flexible filter member 18, which is preferably chamois and has some slack in its central portion.

Screwed onto the partition 16 on the 70 side toward the filter member 18, is a spacing plug 19 for holding the central portion of the chamois filter member away from the partition 16.

Near the lower portion of the part 10 of 75 the casing is a clean out tube 20 communicating with a discharge tube 21 in which is a valve 22. Formed on the upper portion of the part 10 is an intake passage 23, adapted to communicate with the gasoline supply 80 tube 24.

Formed on the lower portion of the part 11 is a discharge passage 25, communicating with a gasoline tube 26 adapted to lead to the carbureter.

85 In the practical use of my improved filter, the parts are assembled with the partition 16 and the filter member 18 in position. The valve 22 is closed, the passages 23 and 25 are connected with the tubes 24 and 26 90 respectively. The device may be placed close to a carbureter so that the fuel is fed through the tube 26 direct to the carbureter. Fuel passing into the casing through the tube 24 and intake passage 25 will drop to 95 the bottom of the portion 10 where sediment and solid matter will settle.

The clear gasoline is filtered through the member 18 which is held spaced from the partition 16 by the member 19, and when the partition rises to the level of the opening 17, such fuel passes into said opening into the part 11 and thence outwardly to the passage 25 and the tube 26. The valve 22 may be opened to remove sediment and the like, and the filter may be flushed as often as desired.

When desirable or necessary the parts 10 and 11 may be unscrewed and separated from each other for the removal, cleaning 110

or replacing of the partition 16, the plug 19 or the filter 18.

In some cases it is desirable to replace the filter 18 frequently.

5 It will be understood that some changes may be made in the construction and arrangement of the parts of my improved filter without departing from its essential features and purposes, and it is my intention to cover by this application and the patent to be issued thereon any such changes which may be included within the reasonable scope of my claims.

I claim as my invention.

15 1. In a fuel filter, a casing comprised of two parts detachably connected together, a rigid partition between the parts, having an opening through it, a filter device forming a partition mounted on one side of said partition, intake and discharge passages communicating with interiors of the respective casing parts, a stop on said rigid partition

for holding part of said filter device spaced therefrom.

2. In a fuel filter, a casing comparatively thin from side to side, comprised of two parts screwed together and formed with opposite shoulders on their interiors at their open ends, a rigid partition received between said shoulders, having an opening through it, a filter device having its edge secured between said partition and one of said shoulders, a stop on said rigid partition for holding part of said filter device spaced from the partition, an intake passage communicating with the upper interior of the casing part having the filter device, a valve controlled, clean out passage in the lower part thereof, and a discharge passage communicating with the interior of the other casing part below the level of the opening in the rigid partition.

Des Moines, Iowa, July 13, 1915.
HANS RASMUSSEN.
